(57) **CLAIM**

The ornamental design for a buckle member, as shown and described.

DESCRIPTION

FIG. 1 is a perspective view of my invention showing the new design;

FIG. 2 is a top view thereof;

FIG. 3 is a bottom view thereof;

FIG. 4 is a right side thereof;

FIG. 5 is a left side view thereof;

FIG. 6 is a front view thereof;

FIG. 7 is a back view thereof;

FIG. 8 is another perspective view of my invention showing the new design in combination with another, unclaimed, buckle component;

FIG. 9 is a top view thereof;

FIG. 10 is a bottom view thereof;

FIG. 11 is a right side thereof;

FIG. 12 is a left side view thereof;

FIG. 13 is a front view thereof; and,

FIG. 14 is a back view thereof.

The broken line portions of the disclosure are for illustrative purposes only and form no part of the claimed design.
